US00D824966S

(12) **United States Design Patent** (10) **Patent No.:** **US D824,966 S**
Kaminski et al. (45) **Date of Patent:** **** Aug. 7, 2018**

(54) **POWDER INJECTOR**

- (71) Applicant: **OERLIKON METCO (US) INC.**,
 Westbury, NY (US)
- (72) Inventors: **Louis A. Kaminski**, Long Beach, NY
 (US); **Robert F. Savill, Jr.**, Levittown,
 NY (US)
- (73) Assignee: **OERLIKON METCO (US) INC.**,
 Westbury, NY (US)

(**) Term: **15 Years**(21) Appl. No.: **29/581,011**(22) Filed: **Oct. 14, 2016**(51) **LOC (11) Cl.** **15-09**(52) **U.S. Cl.**USPC ..... **D15/135**(58) **Field of Classification Search**

USPC D15/135, 138, 144, 144.1, 144.2;

D23/213, 223

CPC B05B 5/03; B05B 5/0531

See application file for complete search history.

Primary Examiner — Patricia A Palasik(74) *Attorney, Agent, or Firm* — Greenblum & Bernstein,
 P.L.C.(57) **CLAIM**We claim the ornamental design for a powder injector, as
 shown and described.**DESCRIPTION**

FIG. 1 shows a left side view of a powder injector;
 FIG. 2 shows a right side view of FIG. 1;
 FIG. 3 shows a cross-section view taken along line 3-3 of
 FIG. 4;
 FIG. 4 shows a front view of FIG. 1;
 FIG. 5 shows a rear view of FIG. 1;
 FIG. 6 shows a top view of FIG. 1; and,
 FIG. 7 shows a bottom view of FIG. 1.
 The broken lines in the drawings depict unclaimed environmental subject matter.

1 Claim, 7 Drawing Sheets(56)
